RAIL BENDER

Lester O. Becker, St. Louis, Mo., assignor to
Joseph Pavelka, St. Louis, Mo.

Application April 27, 1938, Serial No. 204,559

14 Claims. (Cl. 153—38)

The invention relates to rail benders of the screw jack type and consists in novel thrust mechanism and in novel setting and indicating mechanism.

One object of the invention is to reduce the amount of force required to operate the device by providing an anti-friction thrust bearing between relatively movable parts of the device.

Another object of the invention is to house the anti-friction elements so that they will be protected from dirt, etc.

Another object of the invention is to render the device adjustable so that it may be set for successive operations which will result in the same extent of bending of the rail being worked upon.

Another object of the invention is to indicate visibly the setting of the device or the extent of bending which has been effected.

Another object of the invention is to simplify the frame structure of benders of the type involved.

Another object of the invention is to provide a frame bearing for the bender screw nut to reduce or prevent wear of the frame by the screw because of thrusts on the operating lever.

These and other detailed objects of the invention are attained by the structure illustrated in the accompanying drawings, in which—

Figure 1 is a top view of a rail bender embodying the invention and showing the same applied to a straight rail, the latter being shown also (in broken lines) in its bent position.

Figure 2 is a front elevation of the bender.

Figure 3 is a detailed view, on an enlarged scale, of the setting and indicating member which also forms a handle for carrying the bender.

Figure 4 is a transverse section on the line 4—4 of Figure 1 and is drawn to an enlarged scale.

Figures 5 and 6 are vertical transverse sections through the structure shown in Figure 4 and are taken on the corresponding section lines of Figure 4.

Figure 7 is a detail of the ratchet by which the screw feeding nut of the bender is actuated.

Figures 8, 9, and 10 are detail sections taken on the corresponding section lines of Figure 7.

Figure 11 is a view corresponding generally to that shown in Figure 1 but sectioned in part and illustrating a modified structure.

The device shown in Figures 1 to 10 embodies a frame 1, having a central body portion and arms or wings projecting in opposite directions therefrom and terminating in jaws 2 for receiving a track rail or other bar-like members to be

bent. Preferably the major portion of the frame consists of a web 3 disposed in the plane of the bending forces and provided with suitable upstanding reinforcing ribs 4 and 5.

At the center of the device the web merges with a hollow chamber 6 which receives the inner end of the jack-like hollow screw 7. The portion of chamber 6 nearest the face of the device is enlarged in diameter to form a cup-like housing 8 which receives an anti-friction unit 10 comprising inner and outer races 9 and 10, respectively, and a plurality of anti-friction elements such as rollers 11. The inner race is seated against the housing shoulder 12. A nut 13 is seated against outer race 10 and includes a shouldered portion 14 substantially flush with the outer edge of housing 8. A retaining and sealing plate 15 is secured to housing 8 and overlies the outwardly facing shoulder 14 on nut 13. Elements 6 and 8 include cylindrical solid walls 20 and an end wall which substantially enclose units 9—10—11 and protect the same and the portion of screw 7 therein from dirt, etc.

Nut 13 has internal threads engaging the threads of screw 7 and has peripheral ratchet teeth 16 (Figure 7) arranged to be engaged by ratchet pawls 17 mounted in a ratchet block 18 which may be oscillated directly or by a lever 19 inserted in the block socket 20.

Block 18 has spaced recesses 21 for receiving individual pawls 17, the recesses opening into the central aperture for nut 13. The inner end of each pawl is seated against the recess wall, and the outer end of the pawl projects through the open end of the recess to engage the ratchet teeth. Springs 22 tend to thrust pawls into tooth-engaging position, but one pawl will be held out of functioning position by the control bar 23 slidable through a slot in block 18 and individual slots in pawls 17.

Bar 23 has a central portion 24 thick enough to substantially fill the slot in the pawl, and has end portions thin enough to permit relative movement of the pawl. When one outer end of bar 23 is pressed inwardly, the thicker middle portion 45 24 of the bar enters the slot in the pawl at the opposite side of the block and moves it, against the thrust of its spring 22, away from the ratchet teeth 16, at the same time permitting the other pawl to rotate under the thrust of its spring 22 50 into engagement with the ratchet teeth.

With the parts shown as indicated in Figure 7, the oscillation of block 18 will result in positive rotation of the nut in the direction indicated by arrow A. When bar 23 is shifted to the 55

opposite position, then the pawls will be shifted and further oscillation of the block will result in the rotation of nut 13 in the opposite direction.

5 The detail ratchet structure just described forms the subject matter of another application by the present inventor filed Aug. 3, 1940, Serial No. 350,573.

10 A key 25 (Figures 4 and 6) is seated in the wall of chamber 6, and screw 7 is grooved at 26 to slide over key 25. Hence the screw is held against rotation with nut 13 irrespective of any frictional forces and will move inwardly or outwardly of the frame when the nut is oscillated.

15 Ratchet block 18 is held in assembled relation with nut 13 by a screw 27 projecting into an annular groove 28 in the nut. The cap plate 29 secured to the outer face of block 18 covers the pawls and their springs and bar 23 and overlies 20 the joint between the block and the nut to prevent the admission of dirt to the working parts.

The setting, indicating, and handle device comprises a threaded stem 30, detailed in Figure 3, a nut 31 threaded thereon and having a rib 32 25 slidably received in a groove 33 provided on the interior periphery of screw 7. Stem 30 is loosely received in an opening provided in the rear of the frame. Nut 31 opposes a plug 41, or other shoulder, at the inner end of screw 7 and when the 30 stem shoulder 37 is seated against the frame and elements 31 and 41 are engaged, the bending movement of screw 7 terminates.

Normally stem 30 is held against movement in the frame by a set screw 34 provided with a 35 winged head 35 and projectable into a recess 35a in the stem. When the stem is so secured, its handle 40 may be utilized to carry the device from one point to another.

It will be understood that the relative position 40 of the parts indicated in Figure 4 is illustrative only and the location of nut 31 on stem 30 (and accordingly the extent of bending movement of screw 7) may be varied by retracting set screw 34 and rotating stem 30 to feed nut 31 towards 45 or away from the stem handle.

It is preferred that the operator may determine readily the setting of nut 31 on stem 30, and to this end I provide a series of scale markings at 39 on a flattened surface 36 on the side 50 of stem 30 (Figure 3). Markings 39 may indicate inches of movement of the screw 7 from its most retracted position, or may merely indicate arbitrarily different settings of the nut and feeding limits for screw 7. When feed screw 55 7 is retracted to its innermost position and set screw 34 released, handle 40 may be pulled outwardly until nut 31 engages element 41. Stem 30 may then be rotated until any selected one of markings 39 is aligned with the frame surface 60 38. Whereupon stem 30 may be pushed inwardly until elements 37 and 38 contact and set screw 34 is tightened.

Subsequent operation of ratchet 18 to rotate nut 13 in a clockwise direction will feed the bending screw outwardly to the limit permitted by elements 31 and 41. The bending screw may then be retracted by rotating its feeding nut 13 in the opposite direction and the bending operation repeated on another section of the same 70 rail, or of another rail. Upon projection of the screw, the second rail section will be bent to the same extent as the first rail section, and this use of the device may be repeated with the same result until the setting of nut 31 on stem 30 is 75 changed.

Lever 19 in socket 20 is disposed substantially tangent with the outer face of housing 8 and, because of this arrangement, when lever 19 reaches the limit of its downward movement by contact with the frame rib 4 (see Figure 2), it 5 will be substantially horizontal and, accordingly, when the lever is raised for the ratchet pawl to engage another ratchet tooth, the angle which the lever makes with the horizontal will be substantially less than that which would result if 10 the axis of the lever and its socket intersected the axis of the screw and the lever was inclined when in its lowermost position. As will be understood by those skilled in the art, this arrangement makes it possible for the operator 15 to apply his weight more advantageously to the lever under any circumstances, and particularly if the device is being used in a mine passageway, the height of which is restricted.

The modification illustrated in Figure 11 embodies a simpler form of the invention in which the ratchet device is omitted and a nut 45 feeds screw 47 inwardly and outwardly. Leverage on the nut is obtained in the usual manner by the insertion of a bar through the apertures in nut 25 ribs 46. The inner flanged portion of the nut and its thrust bearing 48 are received in a housing 49 formed in the frame of the device as in the structure previously described, and the remaining features of the device, including the indicating and automatic stop handled stem 50, correspond to the structure previously described.

The provision of a closed housing for the inner end of the main screw and its nut and the anti-friction bearing unit serves to protect these 35 parts and to rigidify the frame and to provide an elongated bearing for the bending screw, thereby attaining various objects stated in the introductory portion of the specification.

It will be understood that the housing for the 40 anti-friction thrust bearing and the nut may be used irrespective of the indicating and stop mechanism, and vice versa, although the combination of these two features is desirable. Other changes in the details of the structure 45 may be made without departing from the spirit of the invention and the exclusive use of those modifications coming within the scope of the claims is contemplated.

What is claimed is:

1. In a rail bender, a frame having a cup-like housing with a continuous side wall, a bending screw received in said housing and projecting therefrom beyond the face of the frame, an anti-friction bearing unit surrounding said screw 55 and seated against the inner end of said housing, a screw-engaging nut seated on said bearing unit, and a plate secured to said frame and extending across the open end of said housing apertured for said screw and overlying a portion 60 of said nut to retain the same and said unit in assembled relation with each other and with said frame.

2. In a rail bender, a frame having a cup-like recess with solid walls, an anti-friction bearing unit housed in said recess, the side wall of said recess projecting beyond the outer face of said unit, a nut projecting into said recess and seated on said unit, said nut having a shoulder facing outwardly of said frame and substantially flush with the outer face of said frame surrounding said recess, a retaining plate mounted on said face and overlying said shoulder, a bending screw extending through said nut and unit, 70 75 80 85 90 95

and means for rotating said nut to feed said screw relative to said frame.

3. In a rail bender, a frame, a screw member 5
slidable transversely of said frame, a nut seated
on said frame and threaded on said member and
rotatable to move the latter transversely of said
frame to engage and bend a rail, and an adjust-
able stop device for limiting the rotation of said
screw and the rail bending movement of said
10 member.

4. A rail bender as described in claim 3 which
also includes elements associated with the stop
device for visibly indicating the adjustment of
the same to the operator.

15 5. In a rail bender, a frame, a screw member
slidable transversely of said frame, a nut seated
on said frame and threaded on said member and
rotatable to move the latter transversely of said
frame to engage and bend a rail, and ad-
20 justable means for terminating the movement
of said member at the same point in successive
operations of the bender.

25 6. In a rail bender, a frame, a screw member
slidable transversely of said frame, a nut seated
on said frame and threaded on said member and
rotatable to move the latter transversely of said
frame to bend a rail, an element projecting from
30 said frame and seated thereon, a stop mounted
on said element and adjustable thereon relative
to said frame and member by manipulation of
said element and disposed to engage said mem-
ber to limit its bending movement.

35 7. In a rail bender, a frame, a screw member
slidable transversely of said frame, a nut seated
on said frame and threaded on said member and
rotatable to move the latter transversely of said
frame to bend a rail, an indicating element
40 projecting from said frame, a stop positioned
by said element and opposing a portion of said
member to terminate the bending movement of
said member, said element being arranged to
move said stop to different points to vary the
extent of said bending movement.

45 8. In a rail bender, a frame, a nut rotatably
mounted on said frame, a hollow bending screw
in threaded engagement with said nut and held
against rotation in said frame whereby rota-
tion of said nut will feed said screw, a part slide-
50 able in said hollow screw but held against rota-
tion therein, an element extending into said
frame and the inner end of said hollow screw
and having adjustable engagement with said part
and having a shoulder for engaging the ex-
55 terior of said frame to limit the movement of
said bar, part and screw relative to said frame.

9. In a rail bender, a frame, a nut rotatably
mounted on said frame, a hollow bending screw
in threaded engagement with said nut and held
against rotation in said frame, a nut slide-
60 longitudinally in said hollow screw but held
against rotation relative thereto and against re-
moval through the inner end thereof, an element
disposed axially of said screw and extending
through said frame into said screw and having
65 engagement with said latter-mentioned nut, said
element having a shoulder opposing said frame
for positioning said latter-mentioned nut to limit

the movement of said screw transversely of said
frame.

10. In a rail bender, a frame, a nut rotatably
mounted on said frame, a hollow bending screw
in threaded engagement with said nut and held
against rotation in said frame, a nut slide-
5 longitudinally in said hollow screw but held
against rotation relative thereto and against
removal through the inner end thereof, a rod
disposed axially of said screw and extending
10 through said frame into said screw and having
threaded engagement with said latter-mentioned
nut, an element adjustably mounted on said
frame and movable to and from a position in
15 which it engages said rod to prevent or accom-
modate movement of said rod, whereby said rod
when rotated may feed said latter-mentioned
nut longitudinally of said screw, and when held
20 against rotation by said element may limit the
movement of said nut longitudinally of said
screw.

11. In a rail bender, a bending screw, a frame
having a bending-screw mounting portion and
a rail engaging jaw spaced therefrom transverse-
25 ly of the screw axis, a nut threaded on said screw
and seated on said screw mounting portion for
feeding said screw, said nut having a socket ex-
tending transversely of its length, and a lever
30 seated in said socket for rotating said nut and
movable to a position paralleling said frame.

12. In a rail bender, a frame comprising a web,
a peripheral flange and a central portion, a bend-
ing screw journaled in said central portion, a
screw feeding nut seated on said portion, a
ratchet structure for rotating said nut and com-
35 prising a lever movable upwardly about said
screw as an axis from a position parallel with
said web to shift said ratchet structure to fur-
ther rotate said nut.

13. In a rail bender a frame having a part 40
forming a substantially closed housing with an
open end, a bending screw extending through
said housing and projecting from said open end,
an anti-friction bearing unit seated in said hous-
ing, a screw engaging nut seated on said bear-
ing unit, and a plate secured to said frame and
45 substantially closing the open end of said hous-
ing and retaining said nut in unit in assembled
relation with each other and with said frame
and cooperating with the wall of said housing
50 to exclude dirt from said unit and the portion
of said screw in said housing.

14. In a rail bender a frame with fixed spaced
jaws for engaging a rail, the middle portion of
55 said frame between said jaws including a hous-
ing with a substantially cylindrical side wall,
there being a closure at one end of said housing
and there being an opening at the other end
thereof, an anti-friction bearing unit seated in
60 said housing, a nut seated on said unit and hav-
ing a cylindrical portion substantially closing the
open end of said housing to exclude dirt there-
from, a screw threaded through said nut and
held against rotation, and means for rotating
65 said nut to feed said screw transversely of a line
between said jaws.

LESTER O. BECKER.
